UNITED STATES PATENT OFFICE

WILLIS D. WITTER, OF UTICA, NEW YORK, ASSIGNOR, BY MESNE ASSIGNMENTS, TO AMERICAN LA FRANCE AND FOAMITE CORPORATION, A CORPORATION OF NEW YORK

FIRE-EXTINGUISHER UNIT

Application filed August 3, 1925. Serial No. 47,701.

The object of this invention is a compact pressure-operated foam-type fire extinguisher system constructed as a self-contained unit, adapted to occupy but little floor space, and being thereby specially suited for use on ship-board and in other restricted spaces. The invention consists in the general organization and in the combination therewith of a special valve structure having a single control lever, the operation of which causes the system to operate.

The preferred form of the invention is illustrated in the accompanying drawing wherein

Fig. 1 is a central vertical section of the tanks with the piping and valve structure in elevation;

Fig. 2 a top plan;

Fig. 3 a vertical section on III—III in larger scale, the control valve being open; and,

Fig. 4 is a section on IV—IV.

The two foam-making solutions of standard composition are respectively contained in a main or outer cylindrical container 1 and an inner container 2. The main container rests by its lower end on the floor and constitutes the support for the rest of the apparatus, being wide enough to insure adequate stability although on ship-board the apparatus is desirably strapped to a stanchion or bolted to the deck. The inner container is removably supported in the outer container, at its bottom by seating in a seat on the bottom of the main container and, at its top, by its flange 3 which flange is clamped against the head ring 4 of the main container by the cover plate 5. The interiors of the two containers are thus entirely separate and normally out of communication with each other. Each is provided with a charging opening represented by the chained cover caps appearing in Fig. 2; one of these filling openings is through the cover plate 5 and both openings will be understood to be normally tightly closed.

Pressure for expelling the solutions from the containers into the piping and mixing chamber, is derived from two cylinders of compressed gas, such as CO₂. These cylinders are marked 6 and both are held to the

main containers by bracket straps 7 at their lower ends and by clamp brackets 8 at their upper ends; the latter brackets are jointed and provided with wing-nuts, for easy opening, as appears in Fig. 2, so that the cylinders can be readily removed and replaced.

The two, or more, cylinders are connected by flexible coils of metal tubing 9 to a gas manifold 10, supported on the main container by a bracket 11. This manifold delivers by pipe 12 to a pressure-regulator valve 13 of any suitable design and thence through a pressure gauge 17 to a safety valve 14, and thence to the bottom of the control valve as shown in Fig. 3.

The control valve comprises a valve casing 15 and an interior rotary plug member which is hollow and divided into two compartments, the upper of which, marked 16, is a mixing chamber for the solutions, as presently described, and the lower of which, 17, is a distributing chamber for the pressure-gas. This latter compartment is formed as an open-ended cavity in the inner end of the valve member normally in communication with gas pipe 12 and adapted to register, when the valve member is turned to open position, with two opposite gas outlet ports. These ports are marked 18 and each is provided with a projecting externally threaded nipple; one of them connects by pipe 19 with the outer container, and the other by pipe 20 with the inner container.

The discharge of the solutions is by way of the solution pipes 21 and 22 to the two solution inlet ports 23 and 24 formed on opposite sides of the valve casing. The basic solution is ordinarily contained in the outer container and the inlet port for this solution is larger than the corresponding port for the acid solution; the difference in size is indicated in Fig. 4 wherein it will appear also that the discharge passages are both restricted at the port entrance, which is for the purpose of producing a high velocity or jet-delivery of the entering solutions and forcibly impingement and mixing. The corresponding port passages in the rotary valve member register with the casing inlet ports (23 and 24) simultaneously with the opening of the gas outlet

ports 18 of the gas distributing compartment 17, so that when the pressure is applied, the solution delivery connections are also made.

5 The foam is produced in the interior of the movable member of the control valve and escapes therefrom through the foam port 25 which registers with the opening through the externally threaded hose coupling 25^a when the other ports are open.

10 The hose is coiled and supported on hook-bracket 26 so that it hangs directly against the side of the main container, opposite the gas cylinders and to keep it in compact form, 15 it is located between two lateral arms 27, projecting from the side of the main container. One of these arms terminates in a ring or hook 28 in which the hose nozzle is inserted to keep it from swinging. A normally open 20 nozzle is used, i. e. one which has no shut-off valve to close it, so that there will be no danger of bursting the hose in the event that excessive pressure from the gas cylinders should reach it.

25 It will be understood that the system is put in operation by simply opening the combined mixing chamber and control valve, by means of its handle 29, the movement of which is limited to an arc of 90°. After use, 30 any residual pressure in the system can be vented by opening the blow-off cock 30, the valves on the gas cylinder being first closed. The outer container which holds the basic solution is provided with a drain-cock 31 35 which can be used for removing the basic solution, without discharging the system, when it requires renewing on account of age. The basic solution is ordinarily a solution of bicarbonate of soda and water and in the 40 course of time suffers a decomposition into carbonate of soda which is not efficient for foam production; the acid solution does not deteriorate. Each of the pipe connections between the combined mixing chamber and 45 control valve is provided with a disconnectible pipe-coupling whereby they may be opened and swung to one side to provide space for the opening of the cover 5 or the withdrawal of the inner container when that 50 is necessary.

It will be seen that the apparatus described is exceedingly compact and simple to operate and maintain and that it is adapted for 55 producing foam consisting of proper and constant proportions of the acid and basic solutions and also that it is specially suited for marine use.

The following is claimed:

60 The combination with a fluid pressure container, two containers for component foam-making solutions and a discharge hose, of a unitary control valve structure comprising a hollow valve body interiorly divided into 65 two compartments, a housing for said valve

body, pipe connections from said pressure container to said housing and an inlet therethrough to one of said compartments, outlets therefrom connected to each of said solution containers, pipe connections from each of the latter to the housing and inlets therethrough to the other of said compartments, an outlet from the latter to said discharge hose, said second mentioned compartment being of greater dimension than the inlets from the solution containers and the outlet to the discharge hose, thereby constituting said compartment a mixing chamber for the foam-making solutions, and an operating handle connected to said valve body for moving the same in its housing thereby simultaneously to control the flow paths from the fluid pressure container to the solution containers, from the latter to the mixing chamber and from said chamber to the discharge hose.

85 In testimony whereof, I have signed this specification.

WILLIS D. WITTER.
